FABRIC FEED CONTROL

Karl Fritz Tandel, Chemnitz, Germany, assignor
to C. G. Haubold Aktiengesellschaft, Chemnitz,
Germany, a corporation of Germany

Application February 14, 1936, Serial No. 63,969
In Germany February 26, 1935

8 Claims. (Cl. 26—57)

This invention relates to an improved fabric feed control for stretching, tentering, framing, drying and like machines. It has for its principal object to provide a method and means for the maintenance of constant length values, or piece length, in mesh material and particularly artificial silk knitted material. Heretofore, considerable difficulty has been experienced in treating mesh materials in the said machines, owing to the pieces becoming of unequal length, in spite of the fact that they are fed into such machines with a certain overfeed, that is to say with a speed in excess of that of the travelling chain. This is a serious drawback, because it is essential that precise length should be ensured for every piece. Objectionable length variation may be due partly to the pieces having been worked more or less tightly on the knitting frame owing to different conditions of humidity and temperature. Also, it may be due partly to the pieces having assumed unequal lengths in washing and dyeing. Whatever the causes may be, they are unavoidable.

With alteration in length, mesh material exhibits corresponding alteration in width and alterations in tension occur. In accordance with this invention, these alterations in tension are utilized in connection with the overfeed control of the material, so that the material may be fed faster or slower in accordance with the said alterations. In carrying out the invention, a widthwise tension detector or indicator may be provided in the entry section of a machine of the kind referred to. This detector or indicator may serve for the guidance of an operator exercising manual control of the overfeed adjustment. Or, the said detector or indicator may operate on said adjustment either directly or by way of a relay or servo-mechanism so that the said adjustment is automatically operated in accordance with the movements of the detector or indicator.

The detector or indicator may comprise a detector roller which is pressed forcibly, as by means of a spring or weight, against the web of material in the said entry section. This roller may be operatively connected with a pointer movable over an appropriate scale, so that instant values of widthwise tension can be read off from such an indicator. With manual control, the operator will adjust the overfeed control in accordance with his observations of the indicator so as to restore the correct tension. With automatic control, the movable pointer can be utilized for effecting adjustments of the overfeed control means, as already mentioned.

Stretch indicators are known and these usually comprise indicator means disposed in front of the active section of a machine and a device beyond the same. Also, width indicators are known which comprise a pointer indicating the set or required stretch-width and a second pointer operated by an edge detector under the influence of the issuing web. Tension indicating means are known also for the warp threads in weaving looms. The present invention is distinguished, however, by making use of widthwise detection in connection with the overfeed control in tentering, stretching, drying and like machines.

In order to enable the invention to be readily understood, reference is made to the accompanying drawings which illustrate one practical embodiment of the invention by way of example, in which drawings:—

Figure 1 is a diagrammatic side elevation of a tentering, stretching or drying machine with a widthwise detector in accordance with the invention, parts that are unnecessary for an understanding of the invention being omitted from this diagram.

Figure 2 is a plan of Figure 1.

Figure 3 is a side elevation to a larger scale and in greater detail of the feed section of a machine such as is seen in Figure 1.

Figure 3a is a sectional rear elevation illustrating the power transmission in the machine.

Figure 4 is a front elevation of a detail in Figure 3.

Figure 5 is a view similar to Figure 3 but showing the entry section of the machine to which the feed section of Figure 3 appertains.

Figure 6 is a cross sectional front elevation illustrating the detector mechanism seen in Figure 5.

Figure 7 is an elevation to a still larger scale of the detector indicating dial seen in Figure 6.

Figure 8 is a circuit diagram of an electric relay motor to be controlled by the detector.

Referring to Figures 1 and 2, the tensioning or tentering machine comprises two drying sections T^1 , T^2 beyond the entry section E. The web of material a , entering and travelling in the direction indicated by the arrowheads, passes through the sections E, T^1 and T^2 being engaged or gripped along its edges by means such as hooks or needles on chains h of a known type. One form of such needle chain h is seen clearly in Figure 6. At its entry, the web passes around tensioning tubes or rollers b^1 , b^2 disposed so as to cause the web to travel around a double bend which may be an S-bend, as seen in Figure 3.

The web is then passed over guide rollers *c* and *d* (Fig. 1) to widthwise stretching means *e f g* which may be of the known slat construction indicated in Figure 2. The web then engages the 5 chains *h* and is passed through the entry section *E* to the drying sections *T¹*, *T²*. In the entry section *E* the underside of the web is engaged by a detector roller *n*. In the example illustrated, this roller *n* is supported by arms *o¹ o²* fixed on 10 an axle shaft *r*, the latter being fitted at its ends with arms carrying counterbalance weights *t* which tend constantly to press the roller *n* against the underside of the web *a*. It will be observed that the roller *n* presses against the 15 middle portion of the web so that the latter is bowed or bellied upwards as seen in Figure 6. In the example illustrated in Figure 1 there is an operative connection *u* between the axle shaft *r* and a pointer *v* movable in front of a dial or 20 scale *w*. Thus, deflections of the pointer *v* will give instant indications of detection movements performed by the roller *n* in contact with the web *a*. After passing through the drying sections *T¹*, *T²*, the web *a* finally passes to a delivery 25 device *Z* which may be a known device driven from the machine and adapted for depositing the web in folds.

The tensioning rollers, guide rollers, stretching means *e f g* and chain sprockets *h¹* are mounted 30 in a framing *i*. As seen clearly in Figure 4, the tensioning rollers *b¹ b²* have their ends journaled in discs *b³* mounted on short shafts *b⁴* in bearings in the frame *i*. On a shaft *b⁴* there is a worm wheel *b⁵* in mesh with a worm *b⁶* on 35 a shaft *b⁷* revolvable in bearing brackets *b⁸ b⁹* on the frame *i*. The shaft *b⁷* may be turned by hand wheels *b¹⁰ b¹¹* fixed on its ends. As will be seen from Figure 3, there may be a worm wheel *b¹²* fixed on the shaft *b⁷* and geared with a motor 40 *m* so that the shaft *b⁷* may be turned by the power means instead of by manual operation.

The widthwise stretching rollers *e f g*, which are of known construction and need no particular description, are supported by brackets *e¹ f¹ g¹* on 45 the frame *i*, as shown clearly in Figure 3. On the frame *i* there is also supported a gear box *4* of any desired construction and comprising change gears and a hand lever *41* for changing the gear ratio between a driving wheel *42* and a 50 driven wheel *43*. The latter transmits the drive to the rollers *e f g* as hereinafter explained, these rollers being geared together by end gears *e² f² g²*. The main drive comes from a shaft *1*, Figure 5, which is driven by suitable means such 55 as by belt or rope transmission or by an electric motor, not shown. The shaft *1* is geared with a shaft *11*, these shafts being supported in a framing *k* between the sections *E* and *T¹*. A pulley *2* on the shaft *11* drives a cable *3* which is guided 60 beneath the flooring and passes around and drives a pulley *5*, Figure 3, mounted on the frame *i*. The shaft *50* of the pulley *5* carries a pulley *6* driving a cable *7* passing over a horizontally adjustable guide roller *8* and around the aforesaid wheel *42*. The wheel *43*, receiving its drive 65 from the wheel *42* through the change gears, as already explained, drives a cable *9* passing around a pulley connected with the roller *e*, as seen also in Figure 3a, and over a vertically adjustable guide roller *19* before returning to the wheel *43*. The drive thus transmitted, drives the rollers 70 *e f g*, the latter being intergeared as aforesaid.

The speed of revolution of the widthwise stretching rollers *e f g* which feed the material 75 is alterable by operation of the gear change lever

41 and is greater than the speed of the chain *h*. Consequently the material passes from the rollers *e f g* to the needle chain *h* with overfeed and then travels through the section *E* in which the axle shaft *r* is mounted.

As will be seen from Figure 6, the axle shaft *r* extends between the chain-guiding bars *h² h³* and carries the arms *o¹ o²* which press the roller *n* against the web *a* held by the needle chains *h*. Also, it carries the one or more arms *s* on which the balance weights *t* may be mounted so as to be adjustable, as by screw devices, so that the detection pressure of the roller *n* against the web *a* can be varied. In this development of the similar means shown in Figure 1, and as seen in Figures 15 5 and 6, a cord *s¹* may pass from the arm *s* around the axle *v¹* of the pointer *v* which is movable in front of the dial *w*, which dial may be provided with a scale *w¹* as shown in Figure 7. The cord *s¹* may be weighted at its free end, as 20 shown. The dial *W* is supported by a bracket *W²* Figures 5 and 6.

The detector roller *n* can be made to bear 25 against the web *a* with a predetermined pressure due to the weight *t* on the arm *s*. Consequently, the web *a* is pressed upwards to a greater or lesser extent, see Figure 6. With a given loading, the web will be pressed upwards to a greater extent as more material is fed by the widthwise stretching rollers *e f g*, and to a lesser extent as less material is fed. The detector movements of the roller *n* are indicated by deflections of the pointer *V* over the scale *W¹* of the dial *W*.

A certain tension is predetermined for every 30 kind of material and once this basic tension is determined it can be indicated by a setting of an auxiliary pointer *y*, Figure 7. When the pointer *V* diverges from the auxiliary pointer *y*, the operator is warned that a greater or lesser tension 35 is present in the material than that indicated by the auxiliary pointer *y*. He then regulates the speed of the rope drive *9* to the rollers *e f g* by operating the change lever *41* and adjusting the gear ratio in the gear box *4*. This causes the 40 rollers *e f g* to run slower if the bellying of the web *a*, Figure 6, is too great, or faster if the reverse is the case.

If the deflection of the pointer *V* from the set 45 position of the pointer *y* is only small, it is not necessary to change the gear ratio but correction can be obtained by adjusting the setting of the tensioning rollers *b¹ b²*. For this purpose, the operator revolves the hand wheel *b¹⁰* or *b¹¹* and thereby turns the disc *b³* so that the S-shaped curve of the web *a* in its passage over the rollers *b¹ b²* (see Figure 3) is either increased or reduced, thereby braking or tensioning the web to a greater or lesser extent before it passes to the rollers *e f g*. The tensioning rollers *b¹ b²* are not driven. The shaft *b⁴* may be geared by chain gear *b¹⁵*, 50 Figure 4, with an indicator dial *b¹⁶*, so that the operator can conveniently observe the setting of the rollers *b¹ b²*.

The detector roller *n* can be adapted for exercising automatic control by any appropriate means which may be a purely mechanical transmission or an electrical, hydraulic, pneumatic or like relay. By such means, the desired piece 55 length can be maintained quite irrespective of the attention of the operator. In the embodiment described with reference to Figure 3, the motor *m* is provided for this purpose as already mentioned. The motor *m* may be controlled by the means illustrated in Figure 7, which shows limit contacts *x¹* and *x²* carried by the auxiliary 60

pointer y on each side thereof, and lying in the path of the pointer V . If the pointer V touches either of the contacts x^1 or x^2 , then, in the case of electrical control, an electric impulse is transmitted to the motor control by way of a relay so that the motor revolves in one direction or the other. Thus, the motor m through the gearing b^{12} turns the shaft b^7 in one sense or the other and thus appropriately adjusts the discs b^3 for giving a different setting of the rollers b^1 b^2 and increasing or decreasing the S-bend of the web a .

In the circuit diagram, Figure 8, it is assumed that the motor m is a three-phase induction machine connected with leads m^1 m^2 m^3 , the support means being indicated by D^1 D^2 D^3 . Two three-pole contactor switches s^1 and s^2 are disposed between mains and leads and are adapted for being operated by respective electro-magnetic switches Z^1 and Z^2 . If the pointer V , under control of the roller n responsive to widthwise tension, touches the contact X^1 , current flows from D^2 through the switch Z^1 so that the switch S^1 is closed. Thereupon, the motor m is driven in one direction, say clockwise.

If the pointer V moves in the opposite direction and touches the contact X^2 , then the switch Z^2 is energized by connection between the phases D^2 D^3 and the switch S^2 is closed. Thereupon, the motor m is driven reversely or counter-clockwise.

When the pointer V leaves a contact X^1 or X^2 the corresponding switch Z^1 or Z^2 is de-energized and its switch S^1 or S^2 opens so that the motor m comes to rest.

It is clearly to be understood that the invention is not limited to the particular mechanisms described and illustrated, as they are merely examples of many different mechanisms capable of being adapted for carrying out the invention within the scope of the claims hereto appended.

40 I claim:—

1. Tentering machine for mesh fabrics, comprising tenter chains, means for feeding a web to said tenter chains, a detector roller disposed between the tenter chains, an adjustable loading means for said detector roller, a change gear operable for varying the feed of said web, tensioning means controlling the feed of said web, an adjustment mechanism operable on said tensioning means, a

reversible motor in driving connection with said adjustment mechanism, and motor control means in operative association with said detector roller.

2. In a tentering, stretching, drying or like machine for mesh fabrics, an entry section comprising travelling means for engaging the edges of a web, means for feeding a web to said entry section, a detector in said entry section sensitive to the widthwise tension of the travelling web, and means operative for adjusting the rate of feed of said web in accordance with the widthwise tension of the web as determined by said detector.

3. In a tentering, stretching, drying or like machine for mesh fabrics, an entry section comprising travelling means for engaging the edges of a web, means for feeding a web to said entry section, a detector in said entry section sensitive to the widthwise tension of the travelling web, means operative for adjusting the rate of feed of said web in accordance with the widthwise tension of the web as determined by said detector, and means operatively connecting said detector and said adjusting means.

4. In a device according to claim 2 wherein said detector comprises a roller, means for pressing said roller against said web, and means associated with said roller for indicating the widthwise tension of said web as determined by the movements of said roller.

5. In a device according to claim 2 wherein said detector comprises a roller, loading means for constantly pressing said roller against said web, and means for varying the effective force of said loading means.

6. In a device according to claim 3 wherein said detector comprises a roller, means for pressing said roller against said web, said feed adjusting means being controlled by the movements of said roller.

7. A device according to claim 3, said feed adjusting means being power operated.

8. A device according to claim 3 wherein said detector comprises a roller, said feed adjusting means being power operated and being controlled in accordance with the movements of said roller.

KARL FRITZ TANDEL.
